UNITED STATES PATENT OFFICE

171,460

ANIMATED FIGURE TOY

Paul Reitzer, Sao Paulo, Brazil

Application May 11, 1953, Serial No. 24,934

Term of patent 7 years

(Cl. D34—15)

To all whom it may concern:

Be it known that I, Paul Reitzer, a citizen of the United States of America, residing at Sao Paulo, Brazil, have invented a new, original, and ornamental Design for Animated Figure Toy, of which the following is a specification, reference being had to the accompanying drawing, forming part thereof:

Figure 1 is a front view of the animated figure toy, showing my new design;

Figure 2 is a side view thereof; and
Figure 3 is a rear view of said toy.

I claim:

The ornamental design for an animated figure toy, as shown.

PAUL REITZER.
